Primary Examiner — Thomas Johannes*Assistant Examiner* — Catherine Posthauer(74) *Attorney, Agent, or Firm* — Seed IP Law Group PLLC(57) **CLAIM**

The ornamental design for a disposable cup lid, as shown and described.

DESCRIPTION

FIG. 1 is an isometric top view of a disposable cup lid illustrating my new design;

FIG. 2 is a top plan view thereof;

FIG. 3 is an elevation view thereof;

FIG. 4 is a sectional front elevation view of FIG. 2 taken in the direction of line 4-4;

FIG. 5 is a sectional elevation view thereof, taken in the direction of line 5-5;

FIG. 6 is a sectional elevation view thereof, taken in the direction of line 6-6; and,

FIG. 7 is an isometric view of the underside of the disposable cup lid.

The broken lines are shown for the purpose of illustrating environment and portions of the disposable cup lid that form no part of the claimed design.
